[57] **CLAIM**

The ornamental design for a lighter, as shown and described.

DESCRIPTION

FIG. 1 is a view in perspective of a lighter, showing my new design, looking from the top and from the side.

FIG. 2 is a view in side elevation of the same.

FIG. 3 is a view in front elevation of the same.

FIG. 4 is a view in rear elevation of the same.

FIG. 5 is a top plan view of the same.

FIG. 6 is a bottom view of the same.

FIG. 7 is a view in section of the same, taken along line 7—7 in FIG. 3.

FIG. 8 is a view in perspective of the same, with the cover shown detached.
